Electric horn, having a housing, a cover, a diaphragm, a projector horn, and an electrical apparatus, the cover being provided with a plug portion having a tapering conical machine-finished surface for fitting snugly in a corresponding tapering, conical, outwardly flaring, machine-finished entrance opening in the housing.

UNITED STATES PATENT OFFICE

2,352,602

ELECTRIC HORN

Eric H. Church, Des Plaines, Ill., assignor to
Benjamin Electric Mfg. Company, Des Plaines,
Ill., a corporation of Illinois

Application May 12, 1941, Serial No. 392,999

6 Claims. (Cl. 177—7)

My invention relates to electric horns.

One of the objects of my invention is to produce an improved electric horn of the diaphragm and projector type in which the electric control apparatus is so enclosed as to prevent a flame which might result from an explosion within the enclosure from escaping from the enclosure and igniting any inflammable mixture which might exist in the immediate vicinity.

A further object is to provide an improved adjustable mounting for the coil and cord of the electrical apparatus with respect to the armature.

Further objects and advantages will appear from the description and claims.

In the drawings, in which one embodiment of my invention is shown,

Figure 1 is an axial sectional view of an electric horn on the line 1—1 of Fig. 2;

Fig. 2 is an axial sectional view substantially on the line 2—2 of Fig. 1;

Fig. 3 is an axial sectional view substantially on the line 3—3 of Fig. 1;

Fig. 4 is a bottom view of the horn, with the lower part of the casing or housing broken away.

Referring to the drawings in detail, the construction shown comprises a dished housing 1 which may be a casting, a cover 2 for the housing, a vibratable diaphragm 3, a projector horn 4, and an electrical apparatus mounted on the cover inside the housing for actuating the diaphragm. The projector horn, diaphragm, and electrical apparatus may all be mounted on the cover 2. A plug-in separable connector is provided between the supply wires and the wires leading to the electrical apparatus. This plug-in connector shown in detail in Fig. 3 comprises a receptacle portion 5, secured to the housing by means of screws 6 and a plug-in portion 7 secured to bosses 8 on the under side of the cover by means of screws 9. The supply wires may be connected to the binding terminals 10 on the receptacle. The receptacle contacts 11 are engageable by the blades 12 of the plug-in device when the cover is placed in position on the housing.

In order to prevent any possibility of ignited gases or the like escaping from the housing in the event of an explosion or the like within the housing, the cover is provided with a plug portion 13 having a tapering conical machine-finished surface for fitting snugly in a corresponding tapering, conical, outwardly flaring, machine-finished entrance opening in the housing. The fitting is made so accurately and the distance

from the inner point of contact 14 to the outer point of contact 15 between the machine-finished surfaces is so great that ignited gases cannot reach the atmosphere from the inside of the housing.

In order to clamp the plug part of the cover securely in place in the conical opening in the housing, a clamping ring 16 is provided having an internally threaded skirt portion 17 threaded onto an externally threaded portion of the housing. The inwardly extending flange of this clamping ring may engage any suitable portion of the cover unit. As shown, it engages the outer portion of the annular base 18 of the projector horn. When the clamping ring is screwed down it forces the tapered plug portion 13 snugly into the tapering entrance opening in the housing. The diaphragm and projector horn are secured to the cover by means of screws 19 extending through registering openings in the projector horn, flange, and diaphragm and threaded into blind tapped holes in the cover. Due to the use of these blind tapped holes, there is no possibility of ignited gases escaping at the point of connection between the cover 2 and the diaphragm and horn.

The electrical apparatus shown for operating the diaphragm comprises a single coil winding 20, an E-shaped laminated core 21 about the central arm 22 of which the coil extends, and an armature 23 aligned with the lower edge of the core 21. This armature is connected with the diaphragm 3 by means of a plunger 24 threaded into the armature and extending through a long sleeve 25 on the cover. The sleeve has a smooth bore with which the smooth outer surface of the plunger has a smooth slip fit so that the escape of ignited gases between the plunger 24 and the cylindrical bore of the sleeve 25 is prevented. The escape is of course further hindered by the fact that the diaphragm 3 extends across the upper side of the cover and is provided with a steel ring 26 on one side thereof for effecting a seal. In order to position the diaphragm and plunger 24 accurately, studs 26a are secured to the ring 26 and extend through registering holes in the diaphragm 3 and into registering holes in the cover 2.

The central arm of the E-shaped core has a central opening 27 into which the elongated sleeve 25 extends. This core is supported from the cover by means of a pair of L-shaped brackets 28 having wing portions 29 secured by rivets 30 to the outer arms of the core 21 and having foot

portions 31 adjustably mounted on the screws 32 threaded into the cover 2. The threads of these screws 32 fit tightly in the tapped openings in the cover, and these openings are of sufficient length to prevent ignited gases from escaping at these points. The screws 32 are held firmly in place by means of lock nuts 33 engaging the lower surface of the cover. The L-shaped brackets 28 are held securely in adjusted position by means of two pairs of lock nuts 34 between which the supporting feet 31 are gripped. By means of this adjustment, the gap between the armature and core may be finely adjusted and held in adjusted position.

The make-and-break mechanism for controlling the coil circuit comprises a pair of contacts 35 and 36 to which the wires 37 and 38 are connected, respectively, the contact 35 being spring biased to close. The upper contact is controlled by a control arm 39 secured to a threaded extension of the plunger 24, which lifts the contact 35 when the electromagnet is energized. The relative position of the two contacts may be controlled by means of the adjusting screw 40 threaded into the bracket 41. This bracket 41 and the contacts 35 and 36 may be mounted on a foot portion 42 on the bracket 28 by means of screws 43 extending through registering openings in the bracket and contact and threaded into the foot portion 42. Suitable insulation is provided for the contacts. The connections for the switch contacts comprise the two wires 37 and 38 leading from the contact blades to the switch contacts. It is desirable to provide a condenser 44 in parallel with the switch by means of the wires 45 and 46. The condenser has the effect of helping to snuff out the arc to neutralize the magnetic field quickly. The housing is provided with the usual opening 47 for connection with the conduit through which the feed wires extend. The diaphragm 3 may be secured to the plunger 24 by means of a nut 48 threaded onto a reduced extension of the plunger and extending through an eyelet 49 riveted onto the diaphragm, which eyelet clamps the packing washers 50 in place.

Further modifications will be apparent to those skilled in the art, and it is desired, therefore, that the invention be limited only by the scope of the appended claims.

Having thus described my invention, what I claim and desire to secure by Letters Patent is:

1. An electric horn comprising a dished housing, a cover for said dished housing forming therewith an enclosure, a diaphragm, electrical apparatus mounted on said cover inside said enclosure for actuating said diaphragm, said diaphragm being mounted outside said enclosure and said cover having an opening therethrough, and transmission from said electrical apparatus to said diaphragm passing through said opening, said cover having provision for hindering gas from passing from said enclosure through said opening when an explosion takes place in said enclosure and having provisions for hindering the escape of gas past the peripheral edge of the cover.

2. An electric horn comprising a dished housing, a cover for said dished housing forming therewith an enclosure, a diaphragm, electrical apparatus mounted on said cover inside said enclosure for actuating said diaphragm, said diaphragm being mounted on said cover outside

said enclosure, said cover having a sleeve portion having a long, smooth, cylindrical bore, and transmission between said electrical apparatus and diaphragm comprising a plunger having a smooth slip fit in said cylindrical bore.

3. An electric horn comprising a dished housing, a cover for said dished housing forming therewith an enclosure, a diaphragm mounted on said cover outside said enclosure, a projector horn mounted outside said enclosure, electrical apparatus mounted on said cover inside said enclosure for actuating said diaphragm, said dished housing having a tapering, conical, outwardly-flaring, machine-finished, entrance opening, said cover having a plug portion having a tapering, conical, machine-finished surface for fitting snugly in said conical opening, and a clamping ring surrounding said horn and threaded onto said housing member for exerting pressure on said plug portion to force it snugly into said conical opening.

4. An electric horn comprising a dished housing, a cover for said dished housing forming therewith an enclosure, a diaphragm mounted outside said enclosure, electrical apparatus mounted on said cover inside said enclosure for actuating said diaphragm, said dished housing having a tapering, conical, outwardly-flaring, machine-finished, entrance opening, said cover having a plug portion having a tapering, conical, machine-finished surface for fitting snugly in said conical opening, and a clamping ring threaded onto said housing member for exerting pressure on said plug portion to force it snugly into said conical opening, said diaphragm being clamped between said ring and plug portion.

5. An electric horn comprising a dished housing, a cover for said dished housing forming therewith an enclosure, a diaphragm mounted on said cover outside said enclosure, a projector horn mounted outside said enclosure, electrical apparatus mounted on said cover inside said enclosure for actuating said diaphragm, said dished housing having a tapering, conical, outwardly-flaring, machine-finished, entrance opening, said cover having a plug portion having a tapering, conical, machine-finished surface for fitting snugly in said conical opening, and a clamping ring threaded onto said housing member for exerting pressure on said plug portion to force it snugly into said conical opening, said projector horn having a flange clamped between said ring and plug portion.

6. An electric horn comprising a dished housing, a cover for said dished housing forming therewith an enclosure, a diaphragm mounted outside said enclosure, a projector horn mounted on said cover inside said enclosure for actuating said diaphragm, said dished housing having a tapering, conical, outwardly-flaring, machine-finished, entrance opening, said cover having a plug portion having a tapering, conical, machine-finished surface for fitting snugly in said conical opening, and a clamping ring threaded onto said housing member for exerting pressure on said plug portion to force it snugly into said conical opening, said projector horn having a flange clamped between said ring and plug portion and said diaphragm being clamped between said ring and plug portion.
